UNITED STATES PATENT OFFICE.

COY E. HAMILTON, OF ELKHART, TEXAS.

LIQUID-DISPENSING APPARATUS.

1,194,171.

Specification of Letters Patent.

Patented Aug. 8, 1916.

Application filed April 21, 1915. Serial No. 22,727.

To all whom it may concern:

Be it known that I, COY E. HAMILTON, a citizen of the United States, residing at Elkhart, in the county of Anderson and State 5 of Texas, have invented certain new and useful Improvements in Liquid-Dispensing Apparatus, on which the following is a specification.

This invention relates to improvements in 10 liquid dispensing apparatus, one object of the invention being the provision of an apparatus in which the main supply of liquid, preferably oil, to be dispensed is kept under air pressure so that it will be properly delivered 15 from a low to a higher level, there being disposed above the main supply a drip receiving compartment, which when desired may be drained into the main supply.

A further object of the present invention 20 is the provision of a liquid dispenser which is especially adapted for use in dispensing kerosene and gasoline, the air for providing the feeding pressure being manually supplied as needed, and all parts being constructed 25 and arranged for accessibility.

With the foregoing and other objects in view which will be apparent as the description proceeds, the invention resides in the details as fully set forth in the description 30 and as more particularly claimed.

In the accompanying drawings:—Figure 1 is a top plan view of the complete apparatus. Fig. 2 is a vertical longitudinal sectional elevation of the apparatus.

Referring to the drawings, the numeral 5 designates a base upon which rests the casing 6, and the air supplying pump 7.

The casing 6 is divided by the horizontally disposed partition 8, into a lower supply 40 tank M and an upper drain receiving chamber 9, there being provided a port 10 in the partition so that the overflow liquid may be permitted to flow into the main supply tank, a plug 11 being generally in the 45 port to hold the air pressure in the main supply tank.

In the top of the casing vertically alined with the port 10, is a recess 12, in which is detachably received a perforated cup-shaped member 13 so that any overflow of liquid 50 will be directed into the chamber 9, and also to provide a seat for the can to be filled.

Connected to the main supply tank at one end thereof, or at any convenient place is 55 the pressure gage 13', while disposed exteriorly of the casing 6, and extending from

near the bottom to a point above the top is a pipe 14. This pipe is in communication with the lower portion of the tank M, and is provided at its upper end with the faucet 60 controlled outlet 15, whose outlet end is directly above the recessed portion 12. It will be noted that the pipe 14 at its lower portion is tapped into the bottom of the casing 6 at a point slightly to one side of the vertical alinement of the port 10 with the opening in the top 9 for receiving the cup-shaped member 12 which is removably fitted in said top and by reason thereof access can be had to the pipe on the removal of the member 12 and the plug 11 for cleaning purposes, that is to say, the pipe 14 can be readily cleaned as access may be had through the casing to the lower end thereof. A manually controlled valved connection 16 is provided 65 so that the tube 17 leading from the pump 7 may supply air under pressure to the tank M, so that the liquid will be directed 70 through the pipe 14.

It will thus be seen that when the main 75 tank M has been supplied with the liquid through the port 10 and such port is closed, that the valved connection 16 may be opened and the pump 7 operated to force air up to the desired pressure within the tank M, at 80 which time the valve connection 16 is closed. The liquid will now flow out of the faucet 85 when the same is opened, and any surplus will enter the perforated cup-shaped member 13 and the chamber 9. When it becomes necessary the plug 11 is removed and the liquid will flow from the chamber 9 into the tank M, the air pressure therein having been previously relieved through the connection 16.

What I claim, as new, is:—

A liquid dispensing apparatus, comprising a rectangular shaped tank forming a reservoir, means for supporting the reservoir slightly above a foundation, a partition 100 intermediate of the reservoir and disposed horizontally in spaced parallel relation to the top of said reservoir, and having a threaded aperture, a plug detachably engaged in the threaded aperture, said top of the reservoir being formed with an opening 105 in vertical alinement with the threaded aperture, reticulated cup within the opening and having an annular flange raised on the top of the reservoir concentrical of the opening 110 therein, a supply pipe leading from the bottom of the reservoir to a point above the

cup, a valved faucet on the upper end of the pipe, and a valved compressed air inlet pipe communicating with the reservoir immediately below the partition, the point of communication of the supply pipe with the reservoir being in close proximity to the vertical alinement of the aperture and opening in the partition and top of the reservoir re-

spectively for permitting the cleaning of the pipe.

In testimony whereof I affix my signature in presence of two witnesses.

COY E. HAMILTON.
